US00D982600S

(12) **United States Design Patent** (10) Patent No.: **US D982,600 S**
McDonald (45) Date of Patent: **** Apr. 4, 2023**

(54) **DISPLAY SCREEN WITH GRAPHICAL USER INTERFACE**

(71) Applicant: **OUTPOST INTROS INC.,**
 Wilmington, DE (US)

(72) Inventor: **Dane K. McDonald**, St. Louis, MO
 (US)

(73) Assignee: **OUTPOST INTROS INC.,**
 Wilmington, DE (US)

(**) Term: **15 Years**

(21) Appl. No.: **29/754,780**

(22) Filed: **Oct. 14, 2020**

(57) **CLAIM**

I claim the ornamental design for a display screen with graphical user interface, as shown and described.

DESCRIPTION

The sole FIGURE is a front view of a display screen with graphical user interface showing the new design.

The evenly spaced broken lines illustrate portions of the graphical user interface and environment that form no part of the claimed design. The dash-dot lines illustrate the boundary of the display screen and form no part of the claimed design.

1 Claim, 1 Drawing Sheet
